COMPRESSION CONTROL DEVICE

David F. Foster, Napa, Calif.

Application August 23, 1943, Serial No. 499,651

5 Claims. (Cl. 123—48)

(Granted under the act of March 3, 1883, as
amended April 30, 1928; 370 O. G. 757)

The invention described herein may be manufactured and used by and for the Government for governmental purposes, without the payment to me of any royalty thereon.

This invention relates to a compression control device for internal combustion engines of the gasoline or Diesel fuel type and an object of the invention is to provide means operable manually or automatically for maintaining the engine compression pressure constant during changes in barometric pressure. The invention is particularly adapted for use with aircraft engines and is designed to prevent loss of engine power output at high altitudes.

As is well known, the compression pressure in an engine cylinder depends upon the compression ratio and the pressure of the fuel charge in the cylinder when the inlet valve has just closed. Compression ratio may be defined as the ratio of the volume of the clearance space plus the volume swept by the piston to the clearance space. The pressure of the charge in the cylinder at the beginning of the compression stroke is somewhat below atmospheric and increases and decreases with corresponding changes in the external atmospheric pressure. Hence, with the same compression ratio the lower the external atmospheric pressure, the lower will be the compression pressure and the engine power output. It is apparent, therefore, that a reduction in cylinder pressure due to change from a lower to a higher altitude, results in reducing the power of the engine. Even supercharged engines are susceptible to a loss of compression at high altitudes.

To compensate for the reduction in cylinder pressure due to the rarefied atmosphere encountered at high altitudes and to provide uniform power output for all altitudes, the compression ratio must be varied with regard to changing altitude to keep the compression pressure constant. The compression ratio may be varied by increasing and decreasing the volume of the clearance space and it is to a compression control device operating on this principle that the present invention is directed.

Specifically, the invention provides for varying the compression ratio of internal combustion engines by moving a flat plate into and out of the firing chamber and across the inner surface of the cylinder head to vary the volume of the combustion chamber. The plate may have a rectilinear or a rotary sliding movement and is operated either manually, or automatically by an altimeter or other barometer-controlled means, to

vary the compression ratio with regard to changing altitude.

The construction, operation, and advantages of the invention will be apparent from the following detailed description thereof, reference being made to the accompanying drawings, wherein

Figure 1 is a top plan view of a cylinder construction embodying one form of the compression control device.

10 Figure 2 is a vertical longitudinal section on line 2—2 of Figure 1 in which the compression control member is shown extended into the combustion chamber of the engine cylinder.

Figure 3 is a similar section in which the compression control member is shown in the retracted or high compression ratio condition.

Figure 4 is a top plan view of a cylinder construction embodying a modified form of the compression control member.

20 Figure 5 is a section on line 5—5 of Figure 4, and

Figure 6 is a schematic view of the operating mechanism for the compression control member.

25 In the depicted cylinder construction, the piston 1 is shown at the top of its stroke in the bore of the engine cylinder 2 and in spaced relation to the underside of the cylinder head 3 to provide the usual clearance space or combustion space 4. The cylinder head preferably is of the detachable type and for the purposes of the subject invention is modified from conventional practice to include in a side wall thereof a horizontal recess 5 of substantial area and shallow depth.

30 The recess or slot 5 is adapted to house the compression control member 6 and is located near the top of the clearance space 4 into which it opens through the aperture 7; the upper surface of the slot being a continuation of the underside of the cylinder head 3. The shape and size of the slot is in close accord with the corresponding features of the compression control member so that the member, in its normally retracted position, is adapted to be wholly accommodated within the slot and, when so accommodated, substantially fills the slot with edge portion 8 of the member in the vertical plane of the aperture 7. In the retracted position of the compression control member, therefore, the edge portion 8 thereof forms part of the side wall of the combustion chamber and is curved in conformity with the curvature of the chamber wall. When the compression control member is in fully retracted position within the slot, the volume of the

35 40 45 50 55 clearance space 4 is at its maximum value and

the compression ratio is at its minimum. When the compression control member is moved from its fully retracted position and is caused to extend into the clearance space, the volumetric capacity of the clearance space is reduced in dependence upon the extent of movement of the compression control member, and the compression ratio of the cylinder accordingly will be higher. By employing a compression control member of the proper dimensions and by regulating the movement of the member, the reduction in the normal volume of the clearance space and the consequent increase in the compression ratio may be made to just compensate for the reduction in cylinder pressure due to the instant altitude; thereby maintaining the cylinder compression pressure constant with regard to changing altitude. Decreasing the compression space results also in a proportionally larger fuel charge being drawn into the compression cylinder by the suction or intake action of the piston and insures the proper degree of compression of the charge at the moment of combustion. The compression control member 6 is adapted, during its movement within the clearance space, to slidably engage the inner surface of the cylinder head 3 which in effect provides a rigid support or backing for the extended portion of the compression member. The operation of the compression member may be initiated and regulated by any means or system of control, manual or automatic, which moves the member as the barometric pressure varies from sea level to ceiling altitude. The system of control may include electric, hydraulic, or mechanical units or a combination of all three.

The construction shown in Figures 1 to 3 inclusive illustrate one form or species of the invention in which the control member 6 comprises a rectangular plate slidably mounted in the slot 5; the latter being formed in an extension 8 of the cylinder head 3. Ring segments 10 and 11 at the cylinder end of the slot 5, provide bearing supports and seals for the compression control plate to prevent loss of compression between the clearance space and the slot. In the present instance, the compression control member is illustrated as being automatically operated and for this reason is provided at the outer end with a plunger 12 adapted to be reciprocated in a cylinder 13 forming an integral part of the cylinder head extension 8. Cylinder 13 is connected by pipes 14 and 15 to a suitable source 16 of fluid supply, which source of fluid supply is adapted to be connected with and controlled by a barometer or altimeter 17 of an airplane as shown in Figure 2. In operation, as the airplane ascends to a higher altitude above sea level, the expanding movement of the pressure-sensitive element 18 of the altimeter is suitably transmitted to the piston 19 of the hydraulic control; the piston 19 being thereby moved in such manner as to cause the fluid in pipe 15 to be displaced in the direction of the plunger 12. The pressure exerted against the outer face of the plunger 12 by and during the displacement of the fluid in pipe 15 forces the plunger inwardly of the cylinder 13. This movement of the plunger causes the compression control plate 6 to be moved progressively outwardly of the slot 5 so that a portion thereof extends beneath the inner surface of the cylinder head 3 and fills a portion of the space between the cylinder head and the piston 1, thus reducing the volumetric capacity of the clearance or compression space. The extent of movement of the compression con-

trol plate is dependent upon the degree of displacement of the fluid in the control system and this is controlled by the expansion of the pressure-sensitive element 18. During descent of the airplane from a higher to a lower altitude, the contraction of the pressure-sensitive element of the barometer or altimeter is transmitted to the piston 19 in such manner that the movement of the latter, and the resultant direction of displacement of the fluid, is reverse to that which occurs when the airplane is ascending. Consequently, the pressure of the fluid entering the cylinder 13 through the pipe 14 causes the pressure-control plate to be progressively retracted or withdrawn from the compression space. As the compression control plate is moved inwardly of the cylinder 13, any carbon which may have formed thereon is scraped therefrom by the ring segment 10.

A modified form of compression control device is illustrated in Figures 4 to 6 inclusive. In this form, the compression control member 6 comprises a sector-like disk which is rotatably supported in the similarly shaped slot 5 by a vertical shaft 20 to the lower end of which the disk is attached. The shaft 20 has a bearing support in the cylinder head 3 and terminates at its upper end within a casing 21 attached to or formed integral with the cylinder head. A rocker arm 22 is affixed to the upper end of the shaft 20 and for the purpose of manual control has its free end connected by linkage or other suitable means 23 to the hand lever 24. A tension element, such as the spring 25 anchored at one end to the casing 21 and attached at its other end to the rocker arm 22, normally positions the rocker arm at one limit of its stroke with the compression control disk 6 fully housed within the slot 5. When the hand lever is actuated to move the rocker arm against the tension of the spring, the resultant turning movement of the shaft causes the compression control disk to rotate and be swung outwardly of the slot and into the compression space, thereby reducing the volume of compression space and increasing the compression ratio. During reverse movement of the hand lever, the contraction of the spring causes the compression control disk to recede from the compression space with consequent increase in the volume of the compression chamber and decrease in the compression ratio. To provide for automatic operation of the compression control disk, the free end of the rocker arm is engaged by the push rod 26 of a hydraulic piston 27; contact between the rocker arm and the push rod being substantially maintained by the action of the spring 25. Piston 27 slides in a cylinder 28 formed integral with and within the casing 21. The push rod of the piston 27 operates through the open inner end of the cylinder 28 and is displaced outwardly against the rocker arm 22 by the pressure of oil entering the outer end of cylinder through a conduit 29 leading from a suitable source of oil pressure supply. The passage of the oil into and out of cylinder 28 is governed by a pressure control valve assembly 30 located in the conduit 29 and operated by a suitable electrical system 31, such as a photo cell circuit, which in turn is controlled by an altimeter or barometer 32 in an airplane. Any automatic control system suitable for the object in view may be employed with the subject invention and the specific system herein disclosed is merely representative of one of many possible combinations of known de-

vices in general use adapted to provide for automatic and progressive operation of the compression control member in accordance with changes in altitude of the aircraft. In the disclosed system, a graduated light screen 34 is fixedly mounted on an extension 35 of the indicator shaft of the instrument 32 at the back of the latter for rotation between a light source 36 and a photoelectric cell 37; the screen 34 being a circular member of translucent material and wedge-shaped in cross section so that the light falling upon the photoelectric cell is gradually and uniformly varied over the deflection range of the instrument. The photoelectric cell is contained in an electric circuit including a solenoid 38 operatively associated with a rheostat control arm 39 for positioning the arm relative to the rheostat resistance coil 40 so as to increase and decrease the resistance of the valve-solenoid circuit 41, and hence the strength of the solenoid 42, with increase and decrease in the amount of light passing through the screen to the photoelectric cell. The armature of the solenoid 42 is a needle valve 43 movable to and from a valve seat in a by-pass passage 44 connected with the conduit 29 between the inlet and outlet sides of the assembly 30 and leading back to the oil supply source. The pressure in that part of the conduit 29 between the piston 27 and the valve assembly 30, and the resultant displacement of the arm 22 is governed by the displacement of the by-pass control valve 43 relative to its seat, i. e., variations in the location of the valve between fully opened and closed positions, which in turn is controlled in an obvious manner from and by the altimeter through the interconnecting electrical system. The altimeter or barometer energizes the electrical mechanism to operate the valve and control the flow of oil in response to variance in barometric pressure due to change in altitude whereby the compression control disk is moved inwardly of the compression space during increase in altitude and withdrawn therefrom as the altitude decreases. When the device embodies both manual and automatic means, as shown in Figure 6, a selector control such as the switch 33 may be provided for cutting out the automatic means when manual operation is desired. During the withdrawal of the disk, any carbon formed thereon will be scraped therefrom by the edges of the slot.

From the foregoing, it will be obvious that by reducing the compression space in an aircraft engine cylinder as the barometric pressure varies from sea level to ceiling altitude, the compression pressure will be held constant for all altitudes. The device, therefore, will permit sea level compression ratio, and operation of airplanes, at any given altitude. By providing each cylinder head with a compression control member and synchronizing their movement with the operation of the altimeter, the compression ratios in all of the several explosion chambers of multi-cylinder engines may be properly and simultaneously varied to prevent loss of engine power at altitudes above sea level.

Having thus described the invention, I claim:

1. A compression control for an internal combustion engine comprising, in combination with a cylinder and piston of the engine, a compression control plate mounted flatwise in the head

of the cylinder and movable laterally inwardly and outwardly of the clearance space between the piston and the cylinder head and in sliding contact with the said head to vary the volumetric capacity of the clearance space, and barometric pressure-responsive means operatively connected with the compression control plate for moving the same to vary the volume of the clearance space in accordance with changes in barometric pressure due to changes in altitude whereby to maintain the compression pressure constant from sea level to ceiling altitude.

2. A compression control member for an internal combustion engine comprising, in combination with a cylinder and piston of the engine, a compression control plate mounted in the head of the cylinder for movement laterally into and out of the combustion chamber and adapted during such movement to slidably engage the inner surface of the cylinder head above the piston, and means for moving the said plate.

3. A compression control for an internal combustion engine comprising the combination with a cylinder and piston of the engine, a head on the cylinder defining a clearance space above the piston and provided in a side wall thereof with a horizontal recess of substantial area and shallow depth offset to but opening into the clearance space, a compression control member pivotally mounted in the said recess of the cylinder head for movement about an axis normal to the horizontal plane of the recess whereby it is adapted to be moved laterally into and out of the clearance space between the piston and the head of the cylinder, and means for moving the said member.

4. A compression control for an internal combustion engine comprising the combination with a cylinder and piston of the engine, of a housing of substantial area and shallow depth in the head of the cylinder, and communicating with the clearance space between the piston and the head of the cylinder, a shaft rotatably mounted in the head of the cylinder with its inner end within the housing and its upper end externally thereof, a compression control member attached to the inner end of the shaft and to be accommodated in the said housing, and means at the upper end of the shaft for turning the same to cause the compression control member to be moved inwardly or outwardly of the housing for varying the volumetric capacity of the clearance space.

5. A compression control for an internal combustion engine comprising, in combination, a cylinder, a piston therein, a cylinder head having a recess in a side wall thereof forming a substantially wide and shallow slot disposed in a plane normal to the axis of the cylinder and opening into the combustion chamber at the top of the clearance space between the piston and the cylinder head, a flat plate mounted in the cylinder head for movement inwardly and outwardly of the opening between the clearance space and the slot and being positionably adjustable to be entirely housed within the slot for making available the maximum volume capacity of the clearance space or to be variously extended from the slot into the clearance space and across the inner surface of the cylinder head for reducing the volume capacity of the clearance space, and means for positionably adjusting the plate.

DAVID F. FOSTER.
